DESIGN FOR A STEAM GENERATING BOILER FOR STEAM HEATED FLATIRONS

William Blank, Montreal, Quebec, Canada

Application June 7, 1947, Serial No. 139,528

Term of patent 7 years

(Cl. D49—6)

To all whom it may concern:

Be it known that I, William Blank, a subject of the King of Great Britain and resident of the city of Montreal, in the Province of Quebec, Dominion of Canada, have invented a new, original, and ornamental Design for a Steam Generating Boiler for Steam Heated Flatirons, of which the following is a specification, reference being had to the accompanying drawing, forming a part thereof.

In the accompanying drawing:

Fig. 1 is an end elevational view of a steam generating boiler for steam heated flat irons, showing my new design.

Fig. 2 is a plan view thereof; and

Fig. 3 is a side view taken from the right of Fig. 1 and fragmented for convenience of illustration.

I claim:

The ornamental design for a steam generating boiler for steam heated flat irons, as shown.

WILLIAM BLANK.
